CONTAINER CONSTRUCTION

Benton Blair, Bronxville, N. Y., assignor of forty-five per cent to John C. Blair, Stamford, Conn., and ten per cent to Joseph L. Lamia, Flushing, N. Y.

Application January 24, 1941, Serial No. 375,709

2 Claims. (Cl. 229—51)

This invention relates to a container and more particularly to a container which may be easily and quickly opened.

One of the objects of this invention is to provide a container which is simple, thoroughly practical, and durable in use. Another object is to provide a container of the above character which may be easily and quickly opened. Another object is to provide a construction of the above character which may be easily and inexpensively manufactured. A further object is to provide a construction of the above character, the use of which will require a minimum of change in the wrapping machinery now used with the type of container to be described hereinafter. A still further object is to provide a container of the above character which will be neat and attractive in appearance. Other objects will be in part obvious and in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of the various possible embodiments of my invention,

Figure 1 is a perspective view of the body of the container before the application of wrapping material thereto;

Figure 2 is a perspective view of the container shown in Figure 1 after the insertion of articles therein and the application of adhesive material thereto;

Figure 3 is a perspective view of the container shown in Figure 1 after the wrapping material has been applied thereto; and,

Figure 4 is a perspective view illustrating the manner of opening the container through the application of diagonal pressure thereto.

This invention is directed primarily to that type of container which has four side walls made of cardboard or similar material and is covered with a light transparent paper similar in type to Cellophane. This paper forms the top and bottom walls of the container, providing windows through which the articles within the container may be viewed. This type of container is usually sold at news stands, cigar counters, and like places, and accordingly is usually opened by the purchaser without the aid of any instrument. Because of this and because of the elasticity and great strength of Cellophane paper, in the past great difficulty has been experienced in opening

this type of container. It is another object of this invention to provide a container which overcomes the above-mentioned difficulty, as well as many others.

5 Referring now to the drawing in detail, and to Figure 1 in particular, the body of the container, generally indicated at 10, is preferably made of an elongated strip of light cardboard or similar material. Four creases are made in this strip 10 dividing it into four side walls 11, 12, 13, and 14, and a joining flap 15. The strip is then formed into a rectangular shape by bending it on the creases, and the joining flap 15 is secured by any suitable adhesive material to the free edge of side wall 11. Thus, the side walls of the container are hingedly connected to each other, and said container may be distorted from its normal shape by the application of inward pressure to diagonally opposite corners thereof.

20 Next, the articles of food are placed within the body 10 (Figure 2). These are shown as crackers 16, which are positioned so that they are parallel both to each other and to one juxtaposed pair of the side walls of body 10. After the container is 25 filled, two strips of adhesive material are applied to the center portions of the outside surfaces of side walls 11 and 13. These strips preferably extend from the top to the bottom of the side walls and are indicated at 18 on side wall 13 and by dotted lines 17 on side wall 11.

30 The wrapping material, which forms the top and bottom of the container, is next applied. This material is a light transparent paper, preferably of a type similar to Cellophane, and a sheet is wrapped around body 10 so that it covers side walls 12 and 14 (Figure 3) and the top and bottom or open ends of the container. The free edges of the sheet overlap midway between the top and bottom of side wall 12 and are secured 35 together by any suitable adhesive material to form a joining seam 19. The other edges of the sheet extend outwardly from side walls 11 and 13 a distance approximately equal to one half the width of these walls. As the manner of securing these outwardly extending portions of the sheet to side walls 11 and 13 is substantially similar, the description will be limited to the securing of the sheet to side wall 13.

40 The portions 20, which extend outwardly from the top and bottom edges of the container, are first folded inwardly in contact with the adhesive strip 18, which securely anchors the sheet to body 10. The flaps 22 and 23 are next folded 45 inwardly over portions 20 and are fastened in this position in any suitable manner, such as by a

seal, indicated by dotted line 24. Thus, it can be seen that the transparent paper forms the top and bottom walls of the container, making windows through which the articles of food therein may be viewed. Furthermore, the wrapping material is held in definite relationship with respect to the body of the container by the adhesive strips 17 and 18 on side walls 11 and 13.

When it is desired to open this container, it is gripped between a thumb 25 and a finger 26 (Figure 4) positioned on diagonally opposite corners of the body 10. Next, these corners are pressed inwardly toward each other, causing body 10 to bend on the crease lines between its side walls. This distorts the body's shape, decreasing the distance between corners 28 and 29 and increasing the distance between corners 30 and 31. During the distortion of body 10, relative movement between the transparent sheet and the body is prevented by adhesive strips 17 and 18, which securely anchor the sheet to the body. Thus, as corners 30 and 31 move away from each other, a strain extending diagonally across window 27 (Figure 4) is placed thereon. Finally either one or both of corners 30 and 31 break through window 27, making tears 32 and 33 therein. By means of these tears, window 27 may be easily and quickly removed, permitting ready access to the articles within the container. Thus, it can be seen that securing the transparent paper to the container causes it to coact with the distortion of the container to form tears in the windows thereof, permitting its easy and quick removal.

The use of crackers of the type and packed in the manner described hereinabove may be a material, although not a necessary aid to the opening of this container. Such crackers, which are positioned so that they are parallel to one juxtaposed pair of side walls and are of a size slightly less than the size of the side walls with which they are in parallelism, substantially fill the interior of the container. When pressure is applied to the container diagonal to an open end thereof to distort the container out of its normal shape, the crackers move lengthwise with respect to each other and serve as supports which prevent the side walls from bending inwardly toward each other. Thus, these crackers hold the side walls substantially parallel to each other during the distortion of the container, and as the greatest outward movement of corners 30 and 31 (Figure 4) is obtained when the side walls are parallel during distortion, it may be seen that crackers of the type described may be a material aid to the operation of the construction.

Thus, the Cellophane covering either the open top or bottom of the container may be easily and quickly removed by the application of pressure to any two diagonally positioned corners of the body of the container. It will thus be seen that I have provided a thoroughly practical and durable container of the type described, which may be easily and quickly opened and in which the several objects hereinabove mentioned, as well as many others, are accomplished.

As many possible embodiments may be made of the above invention, and as many changes might be made in the embodiment above set forth, it is to be understood that all matter hereinabove set forth, or shown in the accompanying drawing, is to be interpreted as illustrative and not in a limiting sense.

I claim:

1. An article of manufacture comprising a package in the form of substantially a parallelepiped and comprising, a stack of slidably contacting relatively flat individual articles in face contacting relation one above the other, the top and bottom of the stack being referred to as the end walls, an open-ended container portion formed of cardboard or the like and having four separate side wall members hingedly connected together, two of said side wall members being positioned along said end walls of the stack and the other two wall members extending therebetween along opposite sides of the stack, the lateral dimensions of said articles being such that said articles extend substantially between opposite side walls of said container, and a relatively thin readily frangible wrapper tightly wrapped about said container portion and forming taut sheets extending over and completely enclosing said container portion, said wrapper being adhesively secured to said container portion to prevent relative movement therebetween, whereby when two diagonally opposite hingedly connected edges of the container portion are pressed toward each other, the package is distorted with opposed sides of said container portion substantially retaining their parallel relationship and with the corners of the container portion being effective to initiate tearing action of the enclosure to thereby effect opening of the enclosure.

2. A package as described in claim 1 wherein said wrapper is formed of a single sheet of "Cellophane" or the like having overlapping edges and with the corner portions of the sheet folded and sealed to said two side wall members adjacent said end walls of the stack.

BENTON BLAIR.
